UNITED STATES PATENT OFFICE.

HENRY C. HINE, OF NEW BRITAIN, CONNECTICUT.

SUSPENDERS.

SPECIFICATION forming part of Letters Patent No. 727,796, dated May 12, 1903.

Application filed October 6, 1902. Serial No. 126,004. (No model.)

To all whom it may concern:

Be it known that I, HENRY C. HINE, a citizen of the United States, residing in New Britain, in the county of Hartford and State 5 of Connecticut, have invented certain new and useful Improvements in Suspenders, of which the following is a specification.

This invention, relating to that class of garment-supporters generally known as "suspenders," has for one of its objects to provide a construction whereby thin sheet metal may be employed in making trimmings for suspenders without the parts being cut away at the pivot or the pivot itself being cut by the 15 metal, which has heretofore been objectionable.

A further object is to increase freedom of action, reduce friction, and minimize resistance in the trimming or attachment.

In constructing trimmings, attachments, or equalizers for garment-supporters where the former usually comprises pivoted members difficulty has been experienced in that the thinness of the metal presents a knife-edge which cuts the pivot in two, because of the direct bearing it has on the pivot. The present construction, however, will relieve the strain from the pivot, so that the cutting away is prevented.

In the drawings forming part of this specification, Figure 1 illustrates a suspender provided with the improved trimming. Fig. 2 is a view of the trimming detached from the shoulder-straps and partly broken away to show the construction. Fig. 3 illustrates sectionally a view on the line $\alpha\alpha$, Fig. 2. Fig. 4 is a top plan view of the attachment, partly broken away. Fig. 5 is a perspective view of a hanger, and Fig. 6 is a view of the blank 40 which forms the lever.

Similar characters of reference indicate like parts throughout the drawings.

The attachment comprises a lever A and a hanger B, which are pivoted together, as at 45 1. The lever A constitutes a sheet-metal blank C, which is bent upon itself to form walls 2 3, Fig. 3, and each extremity of said lever is provided with bifurcations 4 5, which preferably are formed by the recesses 6 7 in 50 the blanks C in Fig. 6. Pivots mounted

in said bifurcations are the attachments 8 9, which receive the shoulder-straps D D'.

A hanger B is pivoted to the lever A, as at c, and comprises a member having at one end a portion 10, provided with lateral treads 11 55 12, which bear upon rollers 13 14, carried within the walls 2 3 of said lever A. The lower portion of said hanger B is also provided with eyes 15 16 or like attachments, which receive the button ends E E', respectively.

It will be noted that this attachment comprises two members which are pivoted together and forming an equalizer and that by reason of the rollers provided in the lever 65 the pivot receives no strain from the hanger, but the point of bearing is formed between the lateral treads of the hanger and the faces of the friction-rollers. It will also be seen that the placing of the rollers at points opposite the central draft prevents strain on said pivot from any direction. My invention thus comprises a jointed trimming for a garment-supporter, said trimming comprising the following elements, viz: two members and a series of rollers independently pivoted upon one of said members, the other of said members having curved tread portions riding upon said rollers, and means being provided for retaining said members in coöperative relation. The rollers are independently pivoted—that is, they are mounted upon independent pivots at separate points upon the lever—thereby affording a series of supports upon which the curved edges of the hanger may 75 80 85 freely ride. Preferably both of the members are formed of sheet metal, and one consists of a pair of plates and incloses the other of said members.

Various modifications of structure and assemblage may be resorted to within the scope of this invention so long as the object of reducing friction, increasing freedom, and obviating the cutting away of the parts of the pivoted members of trimmings for suspenders is borne in mind.

Having described my invention, I claim—

1. A garment-supporter comprising shoulder-straps and button ends, a connection therebetween comprising a lever provided 100

with attachments to receive said straps, a hanger carried by said lever and adapted to carry said button ends, and a series of rollers independently pivoted upon said lever and 5 adapted to support said hanger.

2. A garment-supporter comprising shoulder-straps and button ends, a connection therebetween comprising a lever the extremities whereof are provided with attachments 10 for holding said straps, a hanger adapted to receive said button ends pivoted to said lever, series of rollers carried by said lever, and treads on said hanger and adapted to ride on said rollers.

15 3. A garment-supporter, a portion whereof comprises an equalizer having a lever provided with shoulder-strap attachments, a hanger holding the button ends and pivoted to said lever, tread portions formed on the 20 upper part of said hanger, and rollers carried by said lever whereon ride said tread portions.

4. A garment-supporter comprising shoulder-straps and button ends, a connection therebetween comprising a lever provided 25 with attachments to receive the shoulder-straps, a hanger pivoted thereto which receives the button ends, treads formed on said hanger, and rollers carried by said lever and on opposite sides of said hanger whereon the 30 latter is adapted to ride.

5. A garment-supporter comprising shoulder-straps and button ends, a connection therebetween comprising a lever having walls, attachments pivoted to said lever for 35 receiving the shoulder-straps, a hanger adapted to receive the button ends and pivoted to and between said walls, treads formed on said hanger near the pivot, and rollers supported between said walls on opposite sides of said 40 hanger, said rollers being adapted to relieve the strain from said pivot.

6. A garment-supporter comprising shoulder-straps and button ends, a connection therebetween comprising a lever having walls 45 and provided with bifurcations, attachments pivotally mounted in said bifurcations and adapted to receive the shoulder-straps, a hanger pivoted to and between said walls and provided with treads, and rollers carried 50 by said lever on opposite sides of said hanger and which are adapted to support the latter from straining said pivot.

7. A garment-supporter comprising shoulder-straps and button ends, a connection 55 therebetween comprising a lever having walls and provided with bifurcations, attachments pivotally mounted in said bifurcations and adapted to receive the shoulder-straps, a hanger pivoted to and between said walls and 60 provided with treads, and rollers carried by said lever on opposite sides of said hanger

and which are adapted to support said hanger and permit a rocking motion of the latter.

8. A garment-supporter comprising shoulder-straps and button ends, a connection 65 therebetween comprising a lever provided with rollers, and a hanger having treads adapted to operate on said rollers, said hanger being pivoted to said lever at a point intermediate said rollers. 70

9. A garment-supporter comprising shoulder-straps and button ends, a connection therebetween comprising a lever provided with rollers and having attachments to receive said straps, a hanger pivoted to said lever and 75 adapted to carry said button ends, said hanger being provided with treads which bear on said rollers.

10. A jointed trimming for a garment-supporter, comprising two members each being 80 provided with means for attachment to a strap or cord, a series of rollers independently pivoted upon one of said members, and the other of said members having curved tread portions riding upon said rollers, and means being provided for retaining said members in co-operative relation; in combination with straps or 85 cords attached to and loosely connected by the members of said trimming, said straps or cords being provided with means for attachment to a garment. 90

11. A jointed trimming for a garment-supporter, comprising two sheet-metal members each being provided with means for attachment to a strap or cord, whereof one member 95 consists of a pair of plates and incloses the other member, a series of rollers being pivoted at different points between said plates, and said inclosed member having curved edges which ride upon said roller; in combination with straps or cords attached to and 100 loosely connected by the members of said trimming, said straps or cords being provided with means for attachment to a garment.

12. A jointed trimming for a garment-supporter, comprising two sheet-metal members each being provided with means for attachment to a strap or cord, a series of independently-pivoted rollers, and means for retaining said sheet-metal members and said rollers in 105 co-operative relation, so that said sheet-metal members may turn relatively to each other upon said rollers; in combination with straps or cords attached to and loosely connected by the members of said trimming, said straps or 110 cords being provided with means for attachment to a garment. 115
